UNITED STATES PATENT OFFICE

165,863

GOOGLE OR SIMILAR ARTICLE

Thomas V. Paulson, Fallbrook, Calif.

Application November 13, 1951, Serial No. 17,359

Term of patent 7 years

(Cl. D57—1)

To all whom it may concern:

Be it known that I, Thomas V. Paulson, a citizen of the United States, residing in the city of Fallbrook, in the county of San Diego and State of California, have invented a new, original, and ornamental Design for a Goggle or Similar Article, of which the following is a specification, reference being had to the accompanying drawing forming a part thereof.

Figure 1 is a front elevational view of a goggle or similar article showing my new design.

Figure 2 is a top plan view of the same.

Figure 3 is a side elevational view thereof.

I claim:

The ornamental design for a goggle or similar article, as shown.

THOMAS V. PAULSON.
